UNITED STATES PATENT OFFICE.

VINCENT BENDIX, OF CHICAGO, ILLINOIS.

ENGINE STARTER.

1,404,711.

Specification of Letters Patent. Patented Jan. 24, 1922.

Application filed November 17, 1916. Serial No. 131,957.

To all whom it may concern:

Be it known that I, VINCENT BENDIX, a citizen of the United States, residing at Chicago, Cook County, Illinois, have invented 5 certain new and useful Improvements in Engine-Starters, of which the following is a specification.

My invention relates to a starter for an engines, such as a gas engine, and pertains 10 to the transmission or drive interposed between the starting motor and the part of the engine to be started. This transmission is of that type exemplified in patents heretofore issued to me, more particularly No. 1,125,935, dated January 26, 1915, which 15 transmission is characterized by a driving member such as a rotatable screw shaft which is adapted to be driven through a yielding driving connection, such as a coiled 20 spring, connected thereto and to an initial driving shaft, such as the extended armature shaft of an electric motor. This transmission is further characterized by a driving member such as a pinion screw threaded 25 upon the screw shaft for both longitudinal movement thereof and rotary movement therewith and adapted to engage a member or part of the engine to be started, such as the fly wheel thereof.

30 My present invention pertains to a new arrangement and cooperation of the above mentioned parts of the transmission characterized particularly by the location of the yielding driving connection in a position 35 adjacent the starting motor and at the inner end of the screw shaft instead of the outer end, as shown in my patent aforesaid. The screw shaft is capable of an endwise or longitudinal movement and in the present instance the same is normally held inwardly 40 in a direction towards the spring but is capable of a movement outwardly in a direction away from the spring whenever the pinion teeth should abut end to end with the teeth of the fly-wheel, this endwise movement being against the tension of the spring 45 which forms the yielding driving connection and acting to extend such spring. Under this construction and arrangement

50 the clearance space which was provided in the device of my patent aforesaid adjacent the spring and outer end of the screw shaft is dispensed with and all danger of any spring coil dropping into any such space 55 is avoided, and moreover by reason of the fact that the spring is extended instead of

compressed during the longitudinal movement of the screw shaft, the extent of such movement is increased.

In the drawing Fig. 1 is an elevation 60 partly in section illustrating one embodiment of my invention and also illustrating a part of the starting motor and a part of a fly-wheel of the engine to be started; Fig. 2 an elevation of the screw-shaft alone, and 65 Fig. 3 a detail view illustrating another way of securing one of the driving heads to the screw shaft.

Referring to the embodiment of my invention as shown in the drawing, the motor, 70 such as an electric motor, is indicated at A and the same is provided with a driving shaft 1 which may be either a separate shaft driven by the armature shaft or, as herein shown, the armature shaft extended. This 75 shaft has its bearing at its outer end in the bushing 2 arranged in the bearing 3 at the outer end of a supporting bracket 4 which is here shown as secured to the casing of the motor. This shaft is mounted intermediate its length in a bearing 5 in one end of the motor casing.

The screw-shaft 6 is in the form of a sleeve mounted upon the driving shaft 1 with its main screw threads intermediate its 80 length and with other screw threads 6^a at its inner end, the other or outer end of the screw shaft being provided with a collar 6^b, preferably integral therewith. Upon the screw threads 6^a there screws the driving 85 head 7 which also acts as the stop nut for the driving member or pinion hereinafter described. In order to keep the head 7 from unscrewing from the screw shaft a notch 6^c is cut into the end of the screw shaft and 90 a portion of the adjacent metal of the head 7 is riveted into such notch.

The driving member is here shown as a pinion 8 which is screw threaded upon the main threads of the screw shaft and is 100 adapted to mesh with the teeth 9^a of the fly-wheel 9.

The resilient driving connection between the armature shaft and the screw shaft consists of a coiled spring 10 which is connected 105 at its ends with said shafts respectively. In the present instance the connection is not direct but indirect through driving heads, to-wit, the driving head 7 already described and a second driving head 11, which is located adjacent the motor and in advance of the bearing 5. This head is secured to the

driving shaft 1 by means of a bolt or pin 12 and is provided with a cylindrical portion 11^a which extends outwardly towards the inner end of the screw-shaft. The spring 10 5 is provided with eyes 10^a and 10^b, the former engaging the bolt 12 and the latter the stud or short bolt 13 which screws into the driving head 7.

The screw shaft is mounted both for rotary movement and for endwise or longitudinal movement but it is kept in the normal position shown in Fig. 1 with a yielding pressure as by means of the spring 10 which holds the inner end of such screw shaft 15 against the outer end of the cylindrical portion 11^a of the driving head 11. However, the screw shaft is capable of an endwise movement in a direction away from the spring, that is towards the right, there being 20 clearance space provided at 14 between the collar 6^b and the bushing 2 to permit of such endwise movement. This movement is against the tension of the spring 10 and acts to extend or draw out such spring. Consequently in this construction and arrangement of parts there is no clearance space 25 provided adjacent the spring as in the drive of my patent aforesaid and therefore no danger of any coil of the spring lodging 30 or becoming wedged in any such space.

Describing the mode of operation and starting with the parts in their normal position shown in Fig. 1, the starting of the electric motor causes a rotation of the shaft 35 1 and consequent rotation of the screw shaft through the resilient driving connection described. The pinion 8 will thereupon be advanced longitudinally of the screw shaft inwardly towards the motor with the result 40 that the same will mesh with the fly-wheel. When the pinion has reached full mesh and its longitudinal movement has been stopped by the driving head or stop nut 7, it will rotate with the screw shaft and will consequently rotate the fly-wheel. When the engine has started on its own power the increased speed of rotation of the fly-wheel 45 will cause the automatic demeshing of the pinion, which will thereupon move back to the home position shown in Fig. 1, at which time it is resting against the collar 6^b.

If in the meshing operation the pinion teeth and fly-wheel teeth should meet end to end the screw shaft will yield longitudinally, that is it would have an enforced movement toward the right against the tension of the spring 10, until the proper register of the teeth is obtained, whereupon the screw-shaft will move back to normal position shown and the meshing will continue until full meshing is secured.

In Fig. 3 I have shown a modified form of construction of the driving head on the screw-shaft according to which such head 65 15 is secured to the screw-shaft by the key 16

supplemented by the employment of the stud 13 acting as a set screw by screwing inwardly through the wall of the head 15 and against the screw-shaft.

I claim:

1. A starter for engines comprising a rotatable shaft having a yielding longitudinal movement, a driving member mounted thereon for both longitudinal movement thereof and rotary movement therewith, and adapted to operatively engage a part of the engine to be started, and a coiled spring connected with such shaft which in its enforced longitudinal movement due to improper engagement of the driving member moves in a direction away from the spring, whereby the latter becomes extended. 70

2. A starter for engines comprising a rotatable screw shaft having a yielding longitudinal movement, a pinion screw-threaded thereon for both longitudinal movement thereof and rotary movement therewith, and adapted to operatively engage a part of the engine to be started, and a coiled spring connected at one end to the screw shaft and extensible to accommodate said longitudinal movement of the shaft due to improper engagement of the pinion with the engine part. 75

3. A starter for engines comprising a rotatable screw-shaft having a yielding longitudinal movement, a pinion screw-threaded thereon for both longitudinal movement thereof and rotary movement therewith, and adapted to operatively engage a part of the engine to be started, a driving shaft, and a driving connection between the latter shaft and screw-shaft including a coiled spring connected to said shafts, the screw-shaft being movable longitudinally in a direction 100 away from the spring and against the tension thereof when the pinion is stopped in its longitudinal movement by improper engagement with the engine part. 105

4. A starter for engines comprising a rotatable screw-shaft having a yielding longitudinal movement, a pinion screw-threaded thereon for both longitudinal movement thereof and rotary movement therewith, and adapted to operatively engage a part of the engine to be started, a driving shaft, and a driving connection between the two shafts, including a driving head secured to the driving shaft, and a spring connected with such head and the screw-shaft and normally holding the latter shaft towards the head with a yielding pressure but by its expansion permitting said longitudinal movement thereof when the pinion is stopped in its longitudinal movement by improper engagement with the engine part. 110

5. A starter for engines comprising a rotatable screw-shaft having a yielding longitudinal movement, a pinion screw-threaded thereon for both longitudinal movement 115

- thereof and rotary movement therewith, and adapted to operatively engage a part of the engine to be started, a driving shaft, and a driving connection between the two shafts 5 including a driving head secured to the driving shaft, a driving head secured to the inner end of the screw shaft, and a spring secured at its ends to the two heads respectively, said spring normally holding the screw shaft 10 towards the driving head of the driving shaft with a yielding pressure but by its expansion permitting said longitudinal movement thereof when the pinion is stopped in its longitudinal movement by improper engagement with the engine part. 15
6. A starter for engines comprising a rotatable screw-shaft having a yielding longitudinal movement, a pinion screw-threaded thereon for both longitudinal movement 20 thereof and rotary movement therewith, and adapted to operatively engage a part of the engine to be started, a driving shaft, and a driving connection between the two shafts including a driving head secured to the driving shaft, a driving head secured to the inner end of the screw-shaft, and a coiled spring surrounding the first named head and secured at its ends to the two heads respectively, said spring normally holding the 25 screw-shaft against the first named driving head with a yielding pressure but by its expansion permitting said longitudinal movement thereof when the pinion is stopped in its longitudinal movement by improper engagement with the engine part. 30
7. A starter for engines comprising a rotatable screw-shaft having a yielding longitudinal movement, a pinion screw-threaded thereon for both longitudinal movement 35 thereof and rotary movement therewith, and adapted to operatively engage a part of the engine to be started, a driving shaft, and a driving connection between the two shafts including a driving head secured to the driving shaft, a driving head secured to the inner end of the screw-shaft, and a spring secured at its ends to the two heads respectively, said spring normally holding the screw-shaft towards the driving head of the driving shaft 40 with a yielding pressure but by its expansion permitting said longitudinal movement 45
- thereof, when the pinion is stopped in its longitudinal movement by improper engagement with the engine part, said two heads being removably secured to the two shafts 55 respectively. 5
8. A starter for engines comprising a driving shaft, a bearing for the outer end thereof, a sleeve mounted thereon with a clearance space between its outer end and said bearing 60 and having a longitudinal movement outwardly towards said bearing and through said space, a driving member mounted on the sleeve for both longitudinal movement thereof and rotary movement therewith, and a spring driving connection located adjacent the inner end of the driving shaft and connecting between it and the inner end of the sleeve, such spring being arranged to resist said outward movement of the sleeve. 65
9. A starter for engines comprising a driving shaft, a bearing for the outer end thereof, a screw threaded sleeve mounted thereon with a clearance space between its outer end and said bearing, and having a longitudinal movement outwardly towards said bearing and through said space, a pinion screw threaded on the sleeve for both longitudinal movement thereof and rotary movement therewith, and a coiled drive spring located 70 adjacent the inner end of the driving shaft and connecting between it and the inner end of the sleeve, such spring by its expansion permitting said outward movement of the sleeve. 75
10. A starter for engines comprising a driving shaft, a screw-threaded sleeve mounted thereon, a pinion screw-threaded on such sleeve for both longitudinal movement thereof and rotary movement therewith, and a spring driving connection located adjacent the inner end of the driving shaft and connecting therebetween and the inner end of the sleeve, such connection including a coiled spring surrounding the driving shaft and connected at its ends respectively to the shaft and sleeve and such sleeve having enforced longitudinal movement in a direction 80 away from the spring and against the tension thereof. 85

VINCENT BENDIX.
